UNITED STATES PATENT OFFICE.

ORRIN REMENSNYDER, OF SAGINAW, MICHIGAN.

DENTAL MASSAGE DEVICE.

Application filed September 14, 1925. Serial No. 56,333.

This invention is a dental device adapted to be used by the patient for exercising and massaging the gums, especially the gum margins in cases where stimulation is indicated, 5 as in the treatment of certain diseases of the gums, such as pyorrhea.

The treatment of pyorrhea usually includes regular daily stimulation by massaging the gums during or following any of the 10 usual dental treatments, surgical, prophylactic, correction of occlusion, or constitutional.

Treatment of gum diseases has long ago demonstrated that stimulation by massaging 15 could be employed most effectively if means could be devised whereby it would be possible to maintain simultaneous contact of the massaging instrument with the entire margins of the gums, that is to say, the investing tissues, including all sides of the neck of each tooth. It may, therefore, be stated as a fundamental consideration that 20 a satisfactory device for the purpose herein described should be capable of making contact simultaneously over the gum margins, in their entirety, that is, including the interdental spaces.

So far as I am aware, the present invention is the first to embody this fundamental 25 consideration in a practical and successful device for accomplishing the desired results.

Complete contact and manipulation for massaging the entire margins of the gums, and also for cleaning the teeth, is, in my 35 device, attained irrespective of the alignment or irregularities of the teeth, or of the absence of certain teeth. The dentist, moreover, can designate the places of contact, or the points of application of the massaging 40 and cleaning operations to suit the requirements of each individual case; that is, he can select those places where contact is needed, and my appliance will produce simultaneous action in all such places when the patient 45 uses the device.

The appliance is usable where there is bridgework, and wherever there is gum tissue to be treated the massage device closely surrounds and grasps the tooth and operates 50 upon the gum margins with the amount of pressure desired by the patient.

Another advantage of my improvement is that the masticating action attendant upon the use of the appliance also induces consider-

able flow of the mouth secretions, which in 55 many cases is a desirable effect.

With the foregoing and certain other objects in view, which will appear later in the specifications, my invention comprises the devices described and claimed and the 60 equivalents thereof.

Fig. 1 is a part sectional side view of the device in use.

Fig. 2 is a plan view showing the pad 65 cavities.

Fig. 3 is a vertical section, showing teeth in place.

Fig. 4 is a similar vertical section of a modified form of the device.

In carrying out my invention, I provide 70 an elastic, compressible and flexible base member 1, upon which the tooth to be treated may bite, the material of the base being adapted to be yieldingly indented by the crown 2 of the tooth when the biting pressure is applied.

Secured to the said base member are an outer wall 3 and an inner wall 4 that extend up to and have their margins or borders 3^a, 4^a, engaging with the inner and outer or lingual and labial gingival margins 5.

The interior opposing faces of the two walls 3, 4 are preferably fashioned to fit and closely engage the outer and inner face areas 6, 7 of each of the teeth to be treated, as well 85 as the side wall areas 8 being the mesial and distal surfaces of the interdental spaces.

Preferably, the pad member 1 and the wall members 3, 4, are all molded as an integral structure from soft rubber, so the pad fits 90 the teeth as perfectly as if the teeth themselves had been formed by being molded in the pad impressions.

The essential feature, however, is that there shall be a compressible pad which under the pressure of the tooth yields, by being indented, and a pair of inner and outer massaging margins or borders suitably mounted on the sides of the pad, so that when the pad is indented these margins will be forced inward and will also have a slight up-and-down rubbing action. As stated above, and as shown in the drawings, the rims or margins 3^a, 4^a that perform the work of massaging are joined to the compressible pad by being molded integral therewith, and this description will be directed to a device so constructed, but it is to be under-

stood that my invention is not limited to this specific integral molding of the pad and the side walls, but includes in its scope the mechanical equivalents thereof, as set forth in the claims.

This appliance, inserted in the patient's mouth, and supplied with a dentrifice or not, as the case may require, massages simultaneously all of the margins 5, 8 of the 10 gums and in addition cleans the tooth surfaces in their entirety when the patient applies masticating pressure.

The prophylactic and massaging actions above referred to are produced by reason of 15 two essential mechanical qualities possessed by the device. In the first place the base 1, is, as before stated, elastic and compressible and in mastication the tooth crown 2 compresses it. Since the flexible pad in its preferred form closely and completely surrounds and is fashioned in the shape of the various teeth, there is a rubbing action on the tooth surfaces, produced by the up-and-down movement permitted by the compressibility 20 of the base, and this action takes place over the entire area of each tooth that is contacted by the flexible walls 3, 4.

The other essential result attained by reason of the compressibility of the base of the 30 pad during mastication is a pumping and massaging action caused by the said slight up-and-down movement, as indicated by dotted lines in Fig. 3, and the resultant alternate gripping and relaxing movements 35 of the margins or free rims 3^a, 4^a of the pad upon the margins of the gums, as indicated by the arrows.

When the gums are diseased detachment of the gum tissue usually occurs and pockets 40 are often formed. In such cases the slight pumping action above alluded to may cause a small amount of blood to exude. This usually marks the beginning of the healing process accompanied by the formation of 45 new tissue, and is a proper and desirable method of promoting a reattachment.

In cases of this kind the pockets and places of attachment are apt to become filled with pus and débris, but the pumping action produced by my device dislodges and removes it in an effective manner that can 50 not be equaled by means of a tooth brush.

A tooth brush or similar hand manipulated device, especially if operated by the 55 dentist, does not give the patient any opportunity to regulate the intensity or amount of pressure accompanying the massaging action. With my device the patient himself can apply whatever pressure is desired, be- 60 cause the amount of pressure is controlled by the patient's masticating muscles.

One biting action per second is about the normal rate of chewing and if this action be kept up for a half minute, will produce as 65 much massaging of the gums, and do it in

a more thorough manner without missing any of the gums or teeth, than could be obtained by a tooth brush in fifteen or twenty minutes. The dentist has heretofore had practically no control over the massage 70 treatment, unless the patient visited him each day over an extended period of time, because it is not practicable for the patient to correctly massage all of his gum areas by means of a hand manipulated device. 75 The bristles of a brush are not adapted for getting into the narrow spaces between the teeth around the entire area of the gum and there are certain of the gum areas that are probably never reached by a tooth brush. 80

My device may be molded in the usual manner from soft rubber so as to fit one or more of the patient's teeth and their gum tissue, or it may be made in the form of a complete mold to take all of the teeth of 85 the upper jaw and another mold may be made for the teeth of the lower jaw, or if desired, both the upper and lower jaw molds may be molded integral, as shown in Fig. 4.

Having thus described my invention, what 90 I claim and desire to secure by Letters Patent is:

1. A gum-massaging device comprising a compressible elastic base pad member and a wall member secured to said pad member, 95 the rim of said wall member adapted to extend up to and contact with the free margin of the gum tissue and to exert variable pressure against said free margin when a tooth indents and compresses a part of said base 100 pad member by biting upon said base pad member.

2. A gum-massaging device comprising a compressible elastic base pad member and an inner and an outer yieldable wall member secured to said base pad member, the free edges of said wall members adapted to closely conform to and contact with the free margins of the gum tissues to be treated and to exert variable pressure thereon when said tooth is caused to indent and compress a part of said pad member between said walls by biting upon said base pad member. 110

3. A gum-massaging device comprising a compressible elastic base pad member and an inner and an outer yieldable wall member integral with said base pad member, the free edges of said wall members adapted to extend the full exposed length of the teeth and to closely engage and contact with the 115 free margins of the gums throughout their entire extent, including those margins of the gums in the interdental spaces, and to exert variable pressure and suction thereon when parts of said base pad member are indented 120 by the teeth of the user by biting upon said base pad member.

4. A gum-massaging device comprising a compressible elastic base pad member and an inner and an outer wall formed integral 130

with said base pad member and adapted to closely envelop and conform to the shape of a tooth, the free edges of said wall members adapted to extend up to and make contact with the free margins of the gums, and to exert variable pressure and pumping or suction effect thereon when said tooth is caused to indent and compress said base pad member by biting upon said base pad member.

In testimony whereof, I affix my signature.

ORRIN REMENSNYDER.
